[57] CLAIM

The ornamental design for a terminal wire holder, as shown and described.

DESCRIPTION

FIG. 1 is a perspective front view of a terminal wire holder embodying the present design;

FIG. 2 is a perspective rear view thereof;

FIG. 3 is a front view thereof;

FIG. 4 is a top plan view thereof;

FIG. 5 is a rear view thereof;

FIG. 6 is a right side view thereof;

FIG. 7 is a left side view thereof;

FIG. 8 is a bottom view thereof; and,

FIG. 9 is a typical referential view thereof when it is used. The elements shown in broken lines in FIG. 9 are for illustrative purposes only and form no part of the claimed design.
